US0D1087429S

(12) **United States Design Patent** (10) **Patent No.:** **US D1,087,429 S**
(45) **Date of Patent:** **** Aug. 5, 2025**

(54) **LIGHT FIXTURE**

- (71) Applicant: **Brandon Cohen**, Vernon, CA (US)
(72) Inventor: **Brandon Cohen**, Vernon, CA (US)
(73) Assignee: **AMP Plus, Inc.**, Vernon, CA (US)
(**) Term: **15 Years**
(21) Appl. No.: **29/775,487**
(22) Filed: **Mar. 23, 2021**
(51) **LOC (15) Cl.** **26-05**
(52) **U.S. Cl.** **D26/74**
(58) **Field of Classification Search**
USPC D26/24, 60, 61, 72-78, 80-89
CPC F21S 8/00; F21S 8/02; F21S 8/026; F21S
8/028; F21S 8/04; F21V 21/00; F21V
21/02; F21V 21/04

See application file for complete search history.

(57) **CLAIM**

The ornamental design for a light fixture, as shown and described.

DESCRIPTION

FIG. 1 illustrates a bottom perspective view of a new and ornamental light fixture according to a first embodiment; FIG. 2 illustrates a bottom view thereof; FIG. 3 illustrates a top view thereof; FIG. 4 illustrates a right-side view thereof; FIG. 5 illustrates a left-side view thereof; FIG. 6 illustrates a front view thereof; FIG. 7 illustrates a rear view thereof; FIG. 8 illustrates a top perspective view thereof; FIG. 9 illustrates a bottom perspective view of a new and ornamental light fixture according to a second embodiment; FIG. 10 illustrates a bottom view of the light fixture of FIG. 9; FIG. 11 illustrates a top view of the light fixture of FIG. 9; FIG. 12 illustrates a right-side view of the light fixture of FIG. 9; FIG. 13 illustrates a left-side view of the light fixture of FIG. 9; FIG. 14 illustrates a front view of the light fixture of FIG. 9; FIG. 15 illustrates a rear view of the light fixture of FIG. 9; and, FIG. 16 illustrates a top perspective view of the light fixture of FIG. 9.

Broken lines in the drawings depict portions of the light fixture that form no part of the claimed design.
